CANDLE HOLDER

Frank D. Sherwood, Beaver Dam, Wis.

Application December 3, 1935, Serial No. 52,737

1 Claim. (Cl. 67—25)

My invention relates to candle holders and more particularly to the type of candle holder that is used for decorating cakes or the like.

An object of my invention is to provide a means of placing candles around the outside circumference of a cake, without in any way interfering with the decorations or trimmings of the cake.

Another object of my invention is to provide an economical candle holder that may be constructed of a very inexpensive material if desired, and destroyed after it has served its purpose.

Still another object of my invention is to so construct the device that the amount of candles to be held may be varied, provision being made to provide receptacles to be used at will and the candles placed in any desired position.

A still further object of my invention is to provide a candle holder that may be removed when the candles are extinguished and the cake ready for cutting.

These objects and their advantageous ends I attain as hereinafter set forth, reference being had to the accompanying drawing, in which

Fig. 1 shows a plan view of the device.

Fig. 2 is a cross sectional view of the device taken at line A—A of Figure 1.

Fig. 3 is a detailed plan view of the slotted and scored aperture.

Fig. 4 is a perspective view of a part of a cake having the device in position, and

Fig. 5 is a cross sectional view in detail of the candle inserted into a receptacle formed by the tongues of the slotted and scored aperture.

Referring to the drawing in detail, wherein like characters of reference denote corresponding parts, the reference character 10 shows the body of the device, which is made of paper or the like, and can be embossed or decorated in any ornamental manner.

The annular channelled shape of the body portion of the device shown permits its encircling a round cake, but various forms and shapes

may be manufactured to fit any cake. The annular body is provided with two vertically disposed walls. An inner wall 11 and an outer wall 12 support a horizontal section 13. This section 13 has apertures 14 consisting of a circular scored line 15 and slots 16 cut through the material within the scored circle 15 in such a manner that the slots 16 cross one another forming triangular sections 17. These triangular sections 17 act as a support for a candle 18 when same is forced downwardly through the apertures 14 as shown in Figure 5, and retain the candle in a vertical position.

The location of the apertures 14 on the top section 13 may be in any convenient arrangement either in an annular plan or in staggered relation to one another. Likewise the number of apertures 14 may be varied, and candles may be inserted into any number of apertures depending on the arrangement and spacing of same.

The invention is susceptible to various changes in its form and minor details of construction, and the right is herein reserved to make such changes as properly fall within the scope of the appended claim.

Having thus described my invention, what I claim and desire to secure by Letters Patent in the United States, is:

As a new article of manufacture, a holder for candles and the like, comprising a piece of sheet material shaped to form an annular body adapted to be placed over and about a cake or the like and having a channel opening through its lower side, the top wall of the body and channel being provided with a plurality of scorings to form seats for the candles, the portions of said top wall between the scorings being bent inwardly of the said channel when the candles are selectively and forceably engaged in said seats, and out-turned flanges formed at opposite edges of the open side of said channel to increase the footing of the holder.

FRANK D. SHERWOOD.
